UNITED STATES PATENT OFFICE.

ANTON SCHWARZWAELDER, OF MINNEAPOLIS, MINNESOTA.

PROCESS OF AND MECHANISM FOR REMOVING BRAN FROM WHEAT.

SPECIFICATION forming part of Letters Patent No. 288,669, dated November 20, 1883.

Application filed December 4, 1882. (No model.)

To all whom it may concern:

Be it known that I, ANTON SCHWARZWAELDER, a subject of the Emperor of Germany, and who has declared his intention of becoming a citizen of the United States, and who resides at Minneapolis, in the county of Hennepin, in the State of Minnesota, have invented 5 a process of and Mechanism for Removing Bran to Wheat, of which the following specification is a full, clear, and exact description, reference being also had to the accompanying drawings, in which—

Figure 1 is a cross-sectional view, and Fig. 2 is a longitudinal sectional view, of the bran-removing machine. Fig. 3 is a view of a small portion of the perforated iron of the casing, illustrating its construction. Fig. 4 is a view of the barrel or tank holding the bran-loosening compound, and of a series of conveyers and bran-removing machines for conducting the bran-removing process. Fig. 5 is a sectional elevation, and Fig. 6 is a cross-sectional view, of the barrel or tank for holding the bran-softening liquid. Fig. 7 is a view of one end of the feed-spout, conveyer, and liquid-nozzle, illustrating the manner of applying the liquid to the wheat. Fig. 8 is a vertical transverse section in the line x x , Fig. 9, and Fig. 30 9 is a central longitudinal vertical section of an improved construction of conveyer specially adapted to the present purpose.

This invention relates to a process of and mechanism for removing the bran from wheat 35 preparatory to its reduction into flour; and the process consists, as hereinafter explained, in subjecting the wheat-berry, with the bran on it, to the action of water containing lime, for the purpose of moistening and loosening the bran, and then removing the bran and germ by mechanical means; and the invention also consists in the mechanism used for removing the bran.

The wheat-berry has several coatings or layers of bran, the number varying with the different kinds of wheat. Some spring-wheat has two or three coatings or layers of bran, while some winter-wheat has four or five layers. To soften and loosen these layers, I prepare a solution of water and lime in proportions that will cause the solution to loosen the

outer layer when applied in quantity sufficient to moisten the bran. In forming this solution one-quarter of a pound of quicklime is taken, and water enough added to it to form 55 about one pound of slaked lime, and then this mixture is combined with water in the proportion of one pound of the former to about one hundred pounds of the latter. The solution is stored in a vessel containing a stirrer for agitating it, so that the lime and water will be kept thoroughly mixed. The solution is kept heated, by steam or other means, at about blood-heat temperature, and is run out of the vessel onto the grain in quantity sufficient to dampen or moisten the outer layer of bran. The berries of wheat are agitated, so that all or a good part of them are reached and acted upon by the solution, which is allowed to fall in a thin stream or spray, or in 60 drops, onto the bulk of the grain, in quantity sufficient for the purpose. The moistened grain is then run into a "beater," where, by attrition, the moistened and loosened layer is 65 taken from the berries. The berries and detached bran are then separated from each other, and the berries, with the remaining layers of bran thereon, are again treated, as before, with the solution, after which the same steps are 70 followed as in the first instance, and so on until all the layers of bran are all removed. 75

The proportions of lime and water given for producing the solution have been found most satisfactory; but any deviation therefrom not essentially different in effect may be made. 85 Other alkaline solutions not essentially different in strength and effect may be used instead of the lime solution, which, however, is believed to be best, and is preferred by me.

The mechanism illustrated in the accompanying drawings is considered the best for carrying out my process; but I do not wish to be confined thereto.

The illustrated mechanism consists of a barrel or tank, A, in which an agitating device is 95 arranged to be revolved to keep the heavy particles of the lime in motion and prevent them settling upon the bottom of the tank. This agitator consists of an upright shaft, a, adapted to be revolved by gearing b, or other means outside the tank, and is armed with a cross-bar, c, and stirrers d on the inside of the

tank. Stationary rods or fingers *e* may also be arranged in the bottom of the tank, as shown, if desired. A pipe, *m*, connects the barrel with a steam-generator, for the purpose of supplying steam to heat the solution.

Leading from the tank *A* are a series of pipes, *B' B² B³*, for carrying the solution to the troughs *C*, through which the wheat runs to the beater-machines, as hereinafter described. 10 Each pipe is provided with a funnel-shaped mouth-piece, *g*, open at its lower end, which may have its lower end perforated, so that the solution will pass therefrom in a thin stream or series of drops onto the grain; and it may 15 be controlled by a stop-cock. The pipe to the tank which has been employed has a discharge-opening of about three-eighths of an inch in diameter.

While any suitable means may be employed 20 to apply the solution, still I have found that running the wheat into a screw-conveyer, *C*, and allowing a small quantity of the solution to run upon it as it falls into the conveyer, answers the purpose admirably, as the revolving 25 of the conveyer thoroughly mixes the wheat and solution and spreads the solution quite evenly over the grains. The conveyer shown in Figs. 4 and 7 is of the common pattern used in most mills, elevators, &c., and consists in 30 a central shaft, *C*, armed with the worm or screw *C²*, and adapted to be revolved in a stationary casing, *C*. This answers the purpose; but for a more thorough mixing and agitation I prefer using the form shown in Figs. 8 and 35 9. This consists in an outer cylindrical casing, *P'*, adapted to be revolved in any suitable manner suggesting itself to a mechanic, inside of which a shaft, *R*, provided with screw-shaped beater arms or blades *T*, is adapted to 40 be revolved in the opposite direction from the casing *P'*. This apparatus may be constructed in any suitable manner; but for the purpose of illustration I have shown the cylinder *P'* mounted loosely upon the shaft *R* by sleeves 45 or collars *n' n²* upon the heads *P² P³* of the cylinder, while the shaft itself is journaled by its ends in frames *U' U²*, as shown. By this means the shaft and cylinder are free to be revolved in opposite directions, but retain their same 50 relative positions.

One of the sleeves, *n'*, is made longer than the other, and is provided with a pulley, *V*, adapted to be revolved by a belt, *V²*, leading from a counter-pulley, *V³*, on a counter-shaft, 55 *V⁴*, attached to the frame *U'*, as shown. Secured to the shaft *R*, outside the sleeve *n'*, is another pulley, *V⁵*, adapted to be revolved by a belt, *V⁶*, leading from another pulley, *V⁷*, upon the same counter-shaft, *V⁴*, as the pulley 60 *V³*. The pulley *V⁴* is twice the diameter of the pulley *V³*, and the pulley *V⁷* is twice the diameter of the pulley *V⁵*, and the belt *V²* will be crossed, as shown.

When the counter-shaft *V⁴* is revolved, the 65 cylinder *P'* will be revolved in one direction, and the shaft *R*, with its screw-blades *T*, will

be revolved in the opposite direction, and at four times the speed of the cylinder *P'*, by reason of the difference in size of the pulleys and the crossing of one of the belts. The speed 70 of the shaft *R* will be about one hundred revolutions per minute, and the cylinder *P'* about twenty-five revolutions per minute.

The head *P²* will be formed open, with spokes or arms, and a stationary auxiliary head, *P⁴*, 75 will be arranged over the end of the cylinder *P'*, through which the feed-spout *P⁵* is run, the open spokes of the head *P⁴* permitting the grain to flow through it freely to the interior of the cylinder. The grain is discharged through a 80 series of slots, *r'*, into a spout, *r²*, from which it is run to the beater-machine. The grain running through this machine is not only thoroughly mixed and agitated to spread the lime solution, introduced through the spout *P⁵*, 85 over the kernels, but the rapid action of the blades *T* throws the grain with considerable force against the interior of the cylinder *P'*, and thereby detaches and forces off a large amount of the bran that has been loosened by 90 the lime solution, and assists the beater-machines in their work.

The conveyer will be made long enough to hold the wheat in contact with the solution a sufficient length of time to allow the outer layer 95 of the bran to become softened and loosened, and then the wheat is run from the conveyer into the beater-machine before mentioned. The construction of this beater-machine is shown in Figs. 1 and 2, and consists of two 100 heads or end plates, *D' D²*, connected to each other at their lower parts by a semi-cylindrical "trough-shaped" metal casing, *E*, and at their upper parts by curved eccentric plates *F' F² F³* and straight eccentric plates *G' G² G³*, 105 the straight plates being provided on their interior faces with angular diagonal sharp-pointed serrations *g*, as shown, the whole thus forming a hollow casing, the lower half, *E*, in a semi-cylindrical form, and the upper half divided by the tangential plates into angular-shaped recesses *H' H² H³*. As many of the eccentric plates as desired may be employed. 110

I is a shaft mounted in suitable bearings on the heads *D' D²*, and passing through the machine parallel with the semi-cylindrical bottom *E*, the axis of the shaft coinciding with the center line of bottom *E*. Upon this shaft *I*, at suitable points, are two hubs, *K' K²*, having arms *L*, three pair being shown; but as 115 many as desired may be used.

Connecting each alternate pair of the outer ends of the arms *L* are beater-strips *M*. These beater-strips will be arranged in a screw form, as shown, so that in revolving the beaters will 120 not only carry the wheat around and throw it against the sharp-pointed serrations *g*, but will also gradually move it along from the feed end to the discharge end of the machine. The grain is fed in by a spout, *h*, at one end, 125 and discharged through a spout, *i*, at the other end. A portion of the semi-cylindri-

cal plate E (about one-third of its length) will be formed of perforated metal N, through which the bran removed from the wheat escapes, and is thus separated from the wheat 5 to a great extent, and not carried off therewith. By this means the wheat having the outer layer of its bran loosened and softened is caught up by the beaters M and thrown against the sharp serrations g again and again in its 10 passage through the machine, and the loosened bran is torn off and forced out through the perforated metal N, while the shorn wheat passes out through the spout i. The rapid revolution of the beaters twirls the grain so 15 fast that when the berries leave the machine they are dry.

A fan, X, or equivalent device, is used in connection with the last beating-machine, so as to separate the loose bran and germ from 20 the berry. If desired, a fan may be used with each beater-machine of the series, but it is not necessary. As many sets of these beater-machines, conveyers, and pipes for feeding the lime solution to the wheat will be used as 25 there are layers of bran to be removed. The grain passes out of one beater into a conveyer, where it is again acted on by the solution, and then into another beater, and so on till the operation is complete.

30 In the drawings I have shown three sets of beaters; but a greater or less number may be used. Only one conveyer and one of the beater-machines may be used, if desired, by conveying the grain after each treatment up 35 into the hopper and passing it through the process again; but by arranging as many different beater-machines, mixing-conveyers, and lime-solution pipes as there are layers of bran to be removed, much time may be saved.

40 A separate tank may be used for each beater-machine and its conveyer, if desired; or one tank with as many pipes leading from it as there are conveyers may be used, the latter arrangement being preferable.

45 This process is particularly applicable to the removal of the bran and germ from wheat before the berry is reduced; but it may be used for the removal of the hull or coatings of barley, or of any other grain, from which it 50 will remove the coatings in the same way.

Having described my invention and set forth its merits, what I claim is—

1. The process of removing the bran and germs from wheat and other kinds of grain preparatory to grinding or making into flour, which consists in first moistening the grain with an alkaline solution to loosen the bran on the berries, and then subjecting the grain while thus moistened to mechanical attrition 55

or agitation for removing the loosened bran 60 and germ, substantially as herein specified.

2. The process of removing bran and germs from wheat and other kinds of grain preparatory to grinding or making into flour, which consists in first moistening the grain with a 65 solution of one part of unslaked lime in four hundred parts of water, or thereabout, and then subjecting the grain while thus moistened to mechanical attrition or agitation for removing the loosened bran and germ, substantially as herein specified. 70

3. The process of removing the bran and germs from wheat and other kinds of grain preparatory to grinding or making into flour, which consists in first moistening the grain 75 with an alkaline solution to loosen a portion of the bran on the berries, then subjecting the grain while thus moistened to mechanical attrition or agitation for removing the loosened portion of the bran, then repeating the alkaline moistening and mechanical attrition or agitation while the grain is thus moistened until all of the bran and germ is removed, substantially as herein specified.

4. The combination of the storing-tank, the 85 screw-conveyer, and the beater-machine, having angular serrations on its inside face, and a perforated bottom and a revolving beater, substantially as and for the purpose set forth.

5. The combination of the storing-tank, the 90 conveyer composed of a revolving cylinder and a screw revolving in the opposite direction to the cylinder, the beater-machine, having a perforated bottom and angular serrations or ribs on its inside face, and the revolving beater, substantially as and for the purpose set forth. 95

6. The combination of the storing-tank, the series of beater-machines having angular serrations on their inside faces, perforated bottoms and revolving beaters, the screw-conveyers arranged to receive the grain and deliver it to the beater-machines, and the series of tubes or pipes leading from the storing-tank to the beater-machines, substantially as 105 and for the purpose set forth.

7. The beater-machine composed of the cylinder having the serrated eccentric plates on its inside face, in combination with the revolving beater, substantially as and for the 110 purpose set forth.

In testimony whereof I have hereunto set my hand in the presence of two subscribing witnesses.

ANTON SCHWARZWAELDER.
